OPERATING AND COUNTERBALANCING MECHANISM FOR OSCILLATING
TUMBLERS OF FISH CANNING MACHINES

Filed April 12, 1927

UNITED STATES PATENT OFFICE

OTTO C. W. MARKS, OF SAN FRANCISCO, CALIFORNIA

OPERATING AND COUNTERBALANCING MECHANISM FOR OSCILLATING TUMBLERS OF
FISH-CANNING MACHINES

Application filed April 12, 1927. Serial No. 183,187.

In can filler machines particularly the type employed in the salmon packing industry where the salmon is cut and forced under pressure into the can by mechanical means, provision is made for a yielding movement 5 between the drive cam of the apparatus and the oscillating tumbler with which cooperates the fish fork for pressing the fish into the can. This mechanism as at present constructed has many defects, the principal being that there is no provision for the absorption of the shock occasioned by the return of certain of the parts under heavy spring pressure. This shock causes a deterioration 10 and frequent breakage of the parts associated with the tumbler, its operating link, the crank lever associated with the link and the oscillating tumbler cam groove. The shock also places undue strain on the power means at 15 times where the load thereon is very light and the sudden increase of resistance, occasioned by the shock, is extremely detrimental and injurious to the power means for the apparatus.

20 My present invention relates to improvements in shock absorber spring barrels forming the intermediate connection between the operating cam and its associated oscillating tumbler in machines of the above described type, and more particularly to that type of machine now in universal use.

The principal object of the invention is to provide an improved form of connection between the power means and the oscillating tumbler whereby the yielding spring movement between the power means and the oscillating tumbler is provided. To provide a structure wherein a yielding counterbalance for controlling sudden movements of 25 the oscillating tumbler in either direction is provided, and one wherein the counterbalancing effect on the oscillating tumbler can be adjusted or varied.

With the above mentioned and other objects in view, the invention consists in the novel construction and combination of parts hereinafter described, illustrated in the accompanying drawings and pointed out in the claims hereto appended; it being understood 30 that various changes in the form, proportion,

size and minor details of construction within the scope of the claims may be resorted to without departing from the spirit or sacrificing any of the advantages of the invention.

To more fully comprehend the invention, reference is directed to the accompanying drawings, wherein—

Fig. 1 is a view in detail side elevation of that portion of a can filler to which my invention relates and illustrating the main drive shaft, the cam drive connection between the shaft and oscillating tumbler and the yieldable connecting link between the cam operated lever oscillating tumbler; there also being illustrated in side elevation, an oscillating tumbler counterbalancing means, and in full and dotted lines the fish pressing fork.

Fig. 2 is a longitudinal detail sectional view of the upper end of the connection between the oscillating tumbler and the cam operated lever.

Fig. 3 is a transverse sectional view on line 3—3 of Fig. 2.

Fig. 4 is a transverse vertical sectional view on line 4—4 of Fig. 1, viewed in the direction of the arrow.

Fig. 5 is a longitudinal detail sectional view of one of the counterbalancing means 30 for the oscillating tumbler.

In illustrating my present invention and setting forth the same in the present application, the drawings and specifications have not been encumbered with illustrations or description of parts of the apparatus other than that to which the invention relates.

In the drawings, wherein like characters of reference designate corresponding parts throughout the several views, the numerals 40 1 indicate the frame members of a can filler apparatus or a machine for a like purpose.

The frame 1 supports a rotating cam shaft 2 mounting a cam disk 3 provided with a cam groove 4. Receivable in said groove is a 45 cam roller 5 at one end of a crank lever 6, fulcrumed at 7. This structure is the conventional drive apparatus of a well known type of can filler apparatus.

Fulcrumed at 8 to oscillate on a horizontal 50

axis is a semi-circular tumbler 9, the same in cross section being of box-like structure and formed in its periphery with an aperture 10 through which reciprocates the fish engaging fork 11, to which is imparted horizontal movement by a lever 12 to which the end of the fork is connected.

As illustrated in the drawings, the fork is retracted in the opening 10 when the tumbler 9 is oscillated to its uppermost position, and is projected through the opening 10 as tumbler 9 oscillates downwardly. In this movement the fork engages the fish to be packed, and through the action of the tumbler 9 presses the same downwardly into the measure box 9'.

Occasions arise where the resistance offered by the fish is considerable, either due to the measure box being filled or due to the filling of the measure box improperly, and such resistance if not compensated for would bend the fork and injure the apparatus.

The operating connection to compensate for the resistance set up by the fish, when too tightly packed in the measure box, and which will permit the continuance of operation of the parts of the machine, without interrupting the rotation of the cam shaft, is constructed as follows:

Pivotedly connected to the free end of the crank lever 6, is a rod 13, which has linear telescoping movement within a sleeve 14 surrounding the same, the sleeve carrying at one end a tip 15, adjustably threaded thereonto, said tip being fulcrumed at 16 to the side wall of the oscillating tumbler 9, as in Figs. 1 and 4.

At one end, the sleeve has adjustably threaded thereon a collar 17 which forms an abutment for one end of a spring 18, coiled about the sleeve 14. The opposite end of the spring 18 bears against a collar 19, slidably on the upper end of the sleeve 14, the collar bearing against and overlying the collar stop keys 20, receivable in slots 21 in the end of sleeve 14. The collar stop keys 20 also bear against the head 22 of the rod 13, confining the spring 18 between collars 17 and 19, so that its tendency will be to cause an inward telescoping movement of the rod 13 and sleeve 14.

It will thus be observed that with shaft 2 rotating and the ordinary resistance being set up by the pressure of the fork 10 against the fish in pressing the same into the can, that there will be little or no relative telescoping movement between the rod 13 and sleeve 14. Should an undue resistance be offered against the downward movement of the fork 11, greater than that capable of being offset by the spring 18, shaft 2 will continue to rotate and relative movement will take place between rod 13 and sleeve 14. As the shaft 2 rotates the groove 4 to a position where the roller arrives at the end of its path,

in the relative low portion of the cam groove 4, the tension of spring 18 is released, without the liability of the collar 19 contacting with the end of the tip 15 and causing a blow to be imparted to the tumbler, rapidly raising the same and injuring other parts of the machine. The release of the tension on the spring 18 also creates a sudden jerk or application of power proportionate to the strength of the spring and its compression to the shaft 2, due to the roller 4 arriving at one end of the low portion of the cam groove. This strain is often injurious to the apparatus.

The improvement I claim and desire to protect is the provision of means for compensating for this strain and absorbing the shock, which means consists of a percussion cup 23 slidable in a recess 24 in the tip 15 in alignment with the head 22 of the rod 13 and against which the head abuts. A spring 25 is positioned in the recess 24 and forces the cup 23 toward the rod head 22.

It will thus be observed that any rapid or sudden movement of the rod head 22 toward the sleeve tip 15 is resisted by the spring 25, the latter compensating for or absorbing any shock which may be delivered to the tumbler 9.

To resist the free oscillation of the tumbler 9 in either direction from its normal position, is a second object of my invention and in accomplishing it I provide two resisting members, connected with the tumbler side wall above and below its fulcrum 8, by adjustable connecting rods 30 having right and left take-up couplings 30' within their length. Each of said resisting members comprises a guide casing or cylinder 26, having a slotted side wall 27, and in each of which cylinders 100 is longitudinally reciprocable a piston 28, each provided with a crank pin 29 to which is fulcrumed one end of the connecting rod 30, the other end of which is fulcrumed at 31 to one side wall of the tumbler 9.

It will be observed that the fulcrum points 31 for the respective connecting rods 30 are positioned one on either side of the tumbler axis 8, and it is to be understood that when the tumbler 9 is in its normal or neutral position, the tension on springs 32 is uniform.

Cooperating with each of the pistons 28 is a coiled spring 32, the springs being anchored to their respective pistons at one end at 33, and at their opposite end to an adjustable arm 34, carried on a bracket 35.

It will be observed that each of the springs 32 are expansion springs and that the oscillation of the tumbler 9 in either direction from its normal or neutral position will cause 125 an elongation or stretching of one of the springs, and the corresponding contraction of the other, thus the spring tension maintains a uniform balance for the tumbler during its oscillating movement.

I claim:

1. An overload relief for the tumbler of a packing apparatus including a power shaft, comprising a rod connecting the power shaft and tumbler for imparting oscillation to the tumbler on the rotation of the shaft, a sleeve telescoping the rod, said rod and sleeve capable of relative linear movement and their outer ends operatively connected with the power shaft and tumbler, a spring acting to inwardly telescope the rod and sleeve, a second spring opposing the inward telescoping movement of the first spring, tension means acting on opposite sides of the tumbler axis for counterbalancing its oscillation in either direction, and means for independently varying the tension of said means acting on the opposite sides of said tumbler.

2. In overload relief for the tumbler of a packing apparatus, including a power shaft, comprising a rod connecting the power shaft and tumbler for imparting oscillation to the tumbler on the rotation of the shaft, a sleeve telescoping the rod, said rod and sleeve capable of relative linear movement and their outer ends operatively connected with the power shaft and tumbler, a spring acting to inwardly telescope the rod and sleeve, a second spring opposing the inward telescoping movement of the first spring, yieldable tension means acting on opposite sides of the tumbler axis for counterbalancing its oscillation in either direction, and means for independently varying the tension of said means acting on the opposite sides of said tumbler.

In testimony whereof I have signed my name to this specification.

OTTO C. W. MARKS.
